CURLING ROD

Carl A. Reininger, Chicago, Ill., assignor, by
mesne assignments, to Helene Curtis Industries,
Inc., a corporation of Illinois

Application January 8, 1945, Serial No. 571,835

7 Claims. (Cl. 132—42)

1

The invention relates to improvements in curling rods and particularly to a radially contractible hair curling rod of a kind especially adapted for use in the process commonly referred to as cold permanent waving.

In cold permanent waving of hair the hair is divided into a large number of individual tresses which are wound upon curling rods and then are thoroughly saturated with a waving solution. After the waving solution has remained on the wound tress for a predetermined period of time, the wound tress is saturated with a neutralizing solution which washes out the waving solution.

In use, the curling rod is held at its ends in a position for attaching the free end of a hair tress thereto and it is then rolled between the fingers towards the scalp to wind the hair tress thereon. During the winding operation the hair tress obviously is placed under considerable tension with the result that the hair tress is tightly wound upon the curling rod. Because a tightly wound curl prevents free penetration of the waving and neutralizing solutions to the innermost strands of the hair in the curl being processed, the innermost strands frequently are not sufficiently saturated to insure proper conditioning of the hair. It is, therefore, advisable to provide in the curling rod means whereby the wound tress of hair may be made sufficiently loose, prior to the application of the solutions, so as to facilitate the free flow of the solutions to the innermost strands thereof. This desired degree of penetration of the solutions is made possible by the use of a curling rod embodying features of the present invention.

It is, therefore, an object of the present invention to provide a curling rod with novel structural features enabling a contraction of its circumferential area so as to impart looseness to a curl wound thereon and thereby facilitate thorough penetration of the solutions throughout the entire body of the curl.

Another object of the invention is to provide a curling rod of the kind embodying features of the present invention with novel manually actuatable means to cause positive radial contraction and expansion of said rod, and, further, to provide novelly attached means to secure a hair tress wound thereon against unwinding.

Another object is to provide a curling rod with a tubular contractible body easily fashioned from sheet material and provided with easily attached end closures.

Another object is to provide an adjustable curling rod of the kind disclosed herein with means

2

at its ends to facilitate the grasping of said rod during the winding of a hair tress thereon.

Another object is to provide a curling rod of the kind having a contractible body with means to effect expansion and contraction of said body movable into engagement with novel elements formed on the body and shaped to afford maximum contraction and expansion of the body wall.

Another object is to provide a curling rod of the kind embodying features of the present invention with easily removable means for clamping a hair tress to the rod preliminary to the winding of said tress thereon.

Another object of the invention is to provide a radially contractible curling rod with gripping elements at its ends useful for attaching thereto means to retain a hair tress wound thereon.

Other and further objects of the present invention will be apparent from the following description and claims and are illustrated in the accompanying drawing which by way of illustration show a preferred embodiment and principle thereof and which is considered to be the best mode of applying that principle. Other embodiments of the invention embodying the same or equivalent principle may be used and structural changes may be made as desired by those skilled in the art without departing from the present invention and the purview of the appended claims.

30 In the drawing:

Fig. 1 is a perspective view of a curling rod embodying features of the invention.

Fig. 2 is a side elevational view of the curling rod.

35 Fig. 3 is a longitudinal sectional view of the curling rod showing the adjustable element in elevation.

Fig. 4 is an enlarged transverse sectional detail view taken on the line 4—4 of Fig. 2.

40 Fig. 5 is an enlarged transverse sectional detail view taken on line 5—5 of Fig. 3, but omitting the clamp.

Fig. 6 is an enlarged transverse sectional detail view taken on line 6—6 of Fig. 2.

45 The curling rod illustrated in the accompanying drawing and embodying the features of the present invention preferably is shaped substantially cylindrical and has a mid-portion of uniformly contracted diameter which gradually increases towards the ends of the rod to provide end portions of substantially larger diameter. This shape of the curling rod is particularly advantageous in that it enables a hair tress to be wound substantially uniformly thereon with the thickest

portion of the wound tress forming in the middle of the rod and thinning out towards the ends.

The curling rod includes a shaped body 11 preferably fashioned from a sheet of material rolled to the required diameter and shaped so as to provide a mid-portion of substantially smaller diameter than the end portions thereof. As shown, the body 11 gradually increases in diameter outwardly towards each end from the medial portion. The sheet thus formed is fixedly held in the tubular shape illustrated by providing caps 12 and 13 on the ends thereof which caps preferably are formed of sheet material and are provided with circumferential flanges 14 to snugly embrace the related ends of the body 11 and they are secured thereto in any approved manner, such as by welding or soldering. The end cap 12 is provided with an axial opening through which a short rod-like extension 15 projects, which extension is formed integral with and on the outside face of a plug member 16 fitted snugly within the related end of the body 11 inwardly of the cap 12. The plug 16 provides means to reinforce the end of the body 11 and also insures a firm mounting for the extension 15 which has a plurality of uses, all to be described presently.

The other cap 13 is similarly provided with an axial opening 17 to freely receive the portion 18, of reduced diameter, on a stem generally indicated at 19. The stem 19 extends inwardly on the longitudinal axis of the tubular body 11 and is provided on its free inner end with an enlarged portion 21 normally disposed substantially midway between the ends of the body 11. The reduced portion 18 extends outwardly beyond the cap 13 and has, securely mounted on its end, a knob 22 fashioned of any suitable material, such as, for example, plastics.

The stem 19 is adapted to be moved longitudinally through the opening 17 in the end cap 13 so as to vary the relative position of the enlarged portion 21. Such movement is limited in one direction by the knob 22 and in the other direction by a shoulder 23 formed at the inner end of the reduced stem portion 18. The enlarged portion 21 is adapted to cooperate with means on the wall of the curling rod body 11 so as to effect radial contraction or expansion of the medial portion of the curling rod. The curling rod is, of course, suitably formed to enable such contraction and expansion to be accomplished easily and quickly upon movement of the stem 19.

To accomplish this expansion and contraction, the body 11 is provided with a diametrically opposed pair of longitudinal slots 24 substantially coextensive with its length but terminating short of the ends thereof. The provision of such slots defines, in effect, two substantially semi-cylindrical wall portions 25 and 26 in the body 11 and it is these wall portions which are moved into various positions upon manipulation of the stem 19. As shown in Figs. 3 and 4 and 5, each of these wall portions 25 and 26 is provided midway between the ends of the curling rod body 11 with a chordal rib 27 preferably fashioned by striking a portion of the walls 25 and 26 inwardly.

When the stem 19 is in the position illustrated in Figs. 3 and 5 the enlarged end portion 21 of said stem is positioned so as to be in contact with the opposed faces of the chordal projections 27 to thereby hold the wall portions 25 and 26 in a radially extended or spaced-apart relationship. When the stem 19 is shifted into the position shown in Figs. 2 and 4, the enlargement 21 is carried out of alignment with the chordal projec-

tions 27 so as to enable the wall portions 25 and 26 to move inwardly towards each other. Such movement of the wall portions towards each other, or into a curling rod contracted position, results from the inherent resiliency of the material from which the curling rod body is formed. Obviously, were the projections 27 extended longitudinally of the body 11, there might be occasions when the enlargement 21 would shift laterally to one side or the other of such longitudinal projections with the result that no expansion would occur. The presence of the chordal projections eliminates this possibility.

In use, the stem 19 is initially positioned as shown in Fig. 3 so as to hold the curling rod body 11 in its fully expanded position. After the curl has been wound thereon, the stem 19 is then shifted into the position shown in Figs. 2 and 4, thereby enabling the curling rod body 11 to contact. As a result, the curl becomes comparatively loose upon the rod.

The winding of a hair tress upon the rod may best be accomplished by holding said rod at its ends, as by grasping the projection 15 on one end and the knob 22 at the other end. The free end of the tress of hair is then engaged with the rod preferably by means of a clamp 28 provided thereon. As shown, the clamp 28 is formed of an elongated strip of suitable material shaped to conform substantially to the contour of the curling rod body 11 and formed on an end with spaced-apart leg portions 29 each having a detent projection 30 detachably engaged in one of a pair of diametrically opposed holes 31 provided in the curling rod body 11 adjacent one end. Thus it will be observed that the clamp 28 may be moved pivotally into open (Fig. 2) and closed (Fig. 1) positions to facilitate engagement of the end of the hair tress easily.

After a tress of hair has been wound upon the curling rod it is secured against unwinding preferably by means of a strand 32 formed of resilient material, such as rubber. The strand 32 is attached by having one apertured end 33 engaged over the projecting end 18 of the stem 19. The other end of the strand 32 is suitably apertured as at 34 for engagement over the projection 15 on the other end of the rod which engagement is effected upon stretching said strand 32 across the wound curl and passing the extension 15 through the opening 34. If desired, a tab 35 may be provided on the free end of the member 32 to facilitate its being grasped and stretched while being secured to or detached from the projection 15.

It should be evident that the curling rod of the present invention embodies novel features making it highly useful for waving of the hair since it includes means to initially retain the hair tress in place on the rod and novel means for securing the wound hair tress in place even after said tress has been loosened by radial contraction of the rod upon which it is wound. The slots 24 in the curling rod body 11 also have the useful purpose of aiding the penetration and circulation of the waving solutions, and additional means may be provided in the curling rod body 11 to further aid in the penetration of the solution through the wound curl. Such means may be in the form of slots 36 and holes 37 suitably arranged in the semi-cylindrical body portions 25 and 26, and holes 38 may be provided in the clamp 28 for the same purpose.

Although a preferred form of the invention has been described herein, it should be understood

that the features of the invention may be incorporated in curling rods shaped other than the particular shape of the rod illustrated without departing from the spirit of the invention or the scope of the appended claims.

I claim:

1. A curling rod comprising, in combination, a tubular expansible body adapted to have a hair tress wound thereon, caps closing the ends of said body, a plug in one end of said body having a projection extending through the related end cap, a stem housed in said body and having an end portion extending through the other end cap and arranged for slideable movement therein, said stem being adapted when moved into a predetermined position of sliding adjustment to expand the body and a resilient strand connected at an end to said stem, said strand being formed at its other end to be engaged with the projection when said strand is extended lengthwise of the curling rod to retain a hair tress wound thereon.

2. A curling rod comprising, in combination, a thin walled tubular body closed at its ends and having a diametrically opposed pair of longitudinal slots terminating short of its ends, said slots defining like body portions substantially semi-circular in section, diametrically opposed chordal offsets formed in the thin body walls one projecting inwardly of each of said body portions, and means slideable in one body end engageable with said chordal offsets effective to move said body portions outwardly in opposite directions.

3. A curling rod comprising, in combination, a tubular body having a normally contracted radially expansible intermediate portion, a clamp to fasten a hair tress to said body, said intermediate portion and said clamp being perforate, cam means including a stem actuatable to cause said intermediate body portion to be held expanded while the hair tress is being wound thereon, said means being operable to enable said intermediate body portion to contract after said hair tress has been wound thereon, and means on said stem engageable with the curling rod to hold the hair tress against unwinding.

4. A curling rod comprising, in combination, an elongated body adapted to have a tress of hair wound thereon, means adjustable to hold said body expanded while said tress is being wound and to enable the body to contract after the tress is wound, and means carried by said adjustable means and engageable with the rod to secure the wound hair tress against unwinding.

5. A curling rod comprising, in combination, a shaped tubular body having circumferential spaced longitudinal slots terminating short of its ends, a fitting arranged at each end of said tubular body, a member mounted in one of said fittings, said member being movable into opera-

tive engagement with the inner surfaces of the body wall to urge portions thereof outwardly radially, a clamp on said body to secure a hair tress thereto while it is being wound on said body, and

5 means to secure the wound hair tress against unwinding, said means consisting of an elastic strand anchored at an end to said member and adapted to be extended across the wound tress and have its other end engaged with the other 10 of said fittings.

6. A curling rod comprising, in combination, a shaped tubular body having circumferentially spaced longitudinal slots terminating short of its ends, said slots defining spaced intermediate wall 15 portions, a fitting at each end of said tubular body, a member mounted in one of said fittings, said member being movable into operative engagement with said wall portions to urge said portions outwardly radially, a clamp on said body

20 to secure a hair tress thereto while it is being wound on said body, said clamp being removable, and means to secure the wound hair tress against unwinding, said means consisting of an elastic strand anchored at an end to said member and

25 adapted to be extended across the wound tress and have its other end engaged with the other of said fittings.

7. A curling rod comprising, in combination, a shaped tubular body closed at its ends having

30 normally contracted medial portions, an engageable member slidably mounted in one end of said body movable into cooperative engagement with the contracted portion of the body to expand said portion, and a fastening strand detachably carried by said member adapted to be extended across a hair tress wound on said rod and be engaged with the other body end to hold the hair tress from unwinding, said strand when so engaged frictionally restraining the engageable

35 40 member from moving in a direction to operatively engage with the body portion.
